UNITED STATES PATENT OFFICE.

JACOB FOX, OF NEW YORK, N. Y., ASSIGNOR TO THALHEIMER BROTHERS, OF NEW YORK, N. Y., A COPARTNERSHIP COMPOSED OF LENA KLEIN AND HARRY JONAS, BOTH OF EAST ORANGE, NEW JERSEY, AND WILLIAM J. KLEIN, OF SOUTH ORANGE, NEW JERSEY.

DESIGN FOR A BUTTON.

57,324.

Specification for Design.

Patented Mar. 15, 1921.

Application filed July 16, 1920. Serial No. 396,849. Term of patent 3½ years.

To all whom it may concern:

Be it known that I, JACOB FOX, a citizen of the United States, residing at New York, borough of Manhattan, in the county and State of New York, have invented a new, original, and ornamental Design for a Button, of which the following is a specification, reference being had to the accompanying drawing, forming a part thereof.

Figure 1 is a view in front elevation.

Fig. 2 is an edge view or side elevation.

I claim:

The ornamental design for a button, as shown.

JACOB FOX.
